UNITED STATES PATENT OFFICE.

ROBERT PITT, OF PINETOPS, NORTH CAROLINA.

BOTTLE.

No. 830,001.

Specification of Letters Patent.

Patented Sept. 4, 1906.

Application filed March 20, 1906. Serial No. 307,061.

To all whom it may concern:

Be it known that I, ROBERT PITT, a citizen of the United States, residing at Pinetops, in the county of Edgecombe and State of North Carolina, have invented certain new and useful Improvements in Bottles, of which the following is a specification.

This invention comprises a novel form of bottle embodying a plurality of compartments adapted to contain a liquid or liquids of different kinds and having means for removing the contents of each of its compartments one at a time as may be desired by the user of the receptacle. The invention is not only designed as a container for different substances in a single receptacle, but may be used for amusement purposes as a trick device, and the operation and construction of the invention with reference to the above uses will be pointed out more clearly hereinafter.

For a full description of the invention and the merits thereof and also to acquire a knowledge of the details of construction of the means for effecting the result reference is to be had to the following description and accompanying drawings, in which—

Figure 1 is a vertical sectional view of a bottle embodying the invention. Fig. 2 is a horizontal section. Fig. 3 is a sectional view embodying a modification of the invention particularly designed for amusement purposes. Fig. 4 is a side elevation of the bottle shown in Fig. 1.

35 Corresponding and like parts are referred to in the following description and indicated in all the views of the drawings by the same reference characters.

In carrying out the invention a bottle or receptacle embodying the same consists, primarily, of two sections—namely, the body-section 1 and a neck or outlet section 2. In one adaptation of the invention the body-section 1 is of a suitable size and form to receive two or more receptacles 3, the latter being of such a form as to fit snugly within the body-section 1 and not have any play or movement which might take away from the effectiveness of the invention. The inner receptacles 3 may consist of bottles of glass or similar substance, and said receptacles 3 are preferably of like form, as shown most clearly in Fig. 2 of the drawings. Each of the receptacles 3 is provided at its upper end with a short neck 4, forming an outlet therefor, each of which outlets is adapted to register

with an outlet-passage 5 in the neck or outlet section 2 of the device. The passage 5 leads from the central passage 6, forming a continuation and terminating at the upper extremity of the section 2, preferably, and when the two sections 1 and 2 are secured together the latter section is adapted to be adjusted so as to bring the lower end of the passage 5 into register or line with a selected or predetermined one of the outlets 4 of the inner receptacles 3. The sections 1 and 2 are connected together by means of a rod or attaching member 7, the lower end of which is adapted to screw into a threaded opening 70 formed centrally of the body-section 1 and the upper end of which is provided with a suitable screw-head 8, admitting of application of a screw-driver or similar tool in order to adjust the member 7 in such a way as to connect the sections 1 and 2 in a substantial way, but admitting of movement of the latter relative to the former. A washer 9 may be provided below the head 8 of the member 7, and it will be noted that the arrangement 80 of the member 7 is such that it may be readily placed in position by passing it through the passage 6 in the neck or outlet section 2. In order to positively hold the bodies of the receptacles 3 in place in the section 1 of the 85 bottle, it is preferred that an annulus or ring 10 be disposed so that its lower portion bears against the bodies of the receptacles 3, while its upper portion is engaged by the section 2, the frictional contact of said section 90 2 being sufficient to prevent all vertical play of the receptacles 3 and hold the same snugly in the section 1, as before mentioned. The portion of the section 2 which is in contact with the upper extremities of the outlet-necks 4 of the receptacles 3 may be provided with a washer 20 applied thereto in any suitable way, so as to prevent likelihood of leakage or escape of the contents of those receptacles 3 the outlet-openings of which are not 100 in register with the passage 5 of the section 2.

In the actual operation of the invention it will be obvious that the receptacles 3 in the body-section 1 of the bottle may be filled with liquids of different qualities, colors, similar or dissimilar, as may be desired, and whenever it is necessary to pour such liquid from any one of the receptacles 3 the outlet-neck 4 thereof is brought into register with the passage 5 of the section 2, and on inversion of the bottle the contents of such receptacle may be readily poured therefrom and

- out of the bottle through the opening or passage 6 aforesaid. In accordance with the invention, therefore, a single bottle apparently containing a single class of goods may contain liquids or substances of different kinds, which may be displaced from such bottle at the will of the operator. The operator is enabled to ascertain when the passage 5 is in register with a selected one of the outlets 4 by means of the provision of suitable indicating data upon the lower portion and upper portion of the sections 2 and 1, respectively. This indicating data may be in the form of corresponding numerals or letters adapted to be brought into register to determine when the passage 5 is in register with the desired outlet of one of the receptacles 3. It will be obvious that when the passage 5 is not in register with any of the outlets 4 of the receptacles 3 the latter are entirely closed by the section 2, this preventing escape of the contents thereof, and in some instances contamination of such contents would likewise be prevented.
- 25 A modification of the invention is represented in Fig. 3 of the drawings in which the bottle is constructed more particularly for trick or amusement purposes. In this instance the body-section 1 instead of having a plurality of compartments formed by a plurality of inclosed receptacles is made of solid form and provided with a number of compartments 3^a, each of which is adapted to register with the outlet-passage in the neck-section 2. The sections 1 and 2 in Fig. 3 may be attached together in the same way as described hereinbefore; but the construction of the bottle is somewhat simplified by reason of the formation of the compartments 3^a, which are virtually the equivalent of the compartments 3, constituted by the receptacles 3 in the construction of the invention as shown in Figs. 1 and 2. The device shown in Fig. 3 when used for amusement purposes may have the compartments 3^a thereof filled with different-colored balls, trinkets, or similar articles, which at the will of the operator may be removed from the bottle by simple adjustment of the section 2. As a means of mystification, more particularly with reference to its amusement functions, the device hereinbefore described is of particular advantage. Different-colored liquids may be poured out of the same bottle or different kinds of small articles may be taken from a single receptacle, apparently, and the above operations would be such as to completely mystify an audience, for reasons which are readily apparent.
- 60 More specifically describing the modification in Fig. 3, it will be observed that an intermediate section 15 is arranged between the sections 1 and 2, said section 15 being provided with a central opening through which the fastening connecting the sections 1 and 2 passes. The intermediate section 15 is rotatable either independently of or with the sections 1 and 2, and said section 15 is formed with an outlet-passage 16, adapted to be brought into register with the outlet-passage 5 of the section 2 and any one of the compartments 3^a. Furthermore, said passage 16 may be caused to register with a pocket or small auxiliary compartment 17, which is formed in the body of the section 2, extending from the lower end thereof and being closed at its upper end. The provision of the section 15 is to subserve the trick purposes of the invention when it is used as a toy, and the advantages of the above will be noted when the operation of the device as last described is understood. The sections 1, 2, and 15 will be provided with suitable indicating data similar to that shown in Fig. 4 exteriorly thereto, whereby whenever desired the passage 16 may be brought into register with the small pocket or compartment 17, or said passage 16 may be similarly positioned with reference to the passage 5. In practical use a small ball or a number of balls may be arranged in the pocket or compartment 17 of the section 2 by one who knows how to operate the device, and it will then be necessary to bring the passage 16 into register with the compartment 17 in order that the balls in the latter may be displaced therefrom, so as to enter one of the compartments 3^a. After this it will be necessary to bring the passage 16 into register with such compartment 3^a and then bring the passage 5 of section 2 into register with the registering passage 16 and compartment 3^a in order that the articles in the last-mentioned compartment may be caused to pass therefrom out of the neck of the bottle. For one not knowing how to operate the invention it will be seen that it would be very difficult to remove the balls or articles in compartment 17.
- Having thus described the invention, what is claimed as new is—
1. In a bottle or similar receptacle of the class described, the combination of a body-section formed with a plurality of separate compartments, an outlet-section provided with a central passage and also with a laterally-extending outlet-passage communicating therewith, a rod pivotally connecting the two sections to admit of the outlet-passage being turned into registry with any one of the before-mentioned separate compartments in the body-section, the said rod being disposed in alinement with the before-mentioned central passage in the outlet-section and being screwed into the body-section, the head of the rod engaging with the bottom of the central passage so as to be readily accessible through the same.
  2. In a bottle or similar receptacle of the class described, the combination of a body-section formed with a plurality of separate

compartments, an outlet-section provided with a central passage and also with a laterally-extending outlet-passage communicating therewith, a washer interposed between the 5 two members and provided with an opening adapted to register with the before-mentioned outlet-passage, and a rod pivotally connecting the two sections and admitting of the outlet-passage being turned into registry with any 10 one of the separate compartments in the body-section, the said rod being disposed in alignment with the before-mentioned central opening in the outlet-section and being screwed into the body-section, the head of the rod engaging 15 with the bottom of the central passage and being readily accessible therethrough.

3. In a bottle or similar receptacle of the

class described, the combination of a body-section, a plurality of separate receptacles arranged therein, an annular ring surrounding the separate receptacles and holding them against movement within the body-section, and an outlet-section applied to the body-section and provided with an outlet-passage, the said outlet-section being adjustable to throw the outlet-passage into registry with a selected one of the before-mentioned receptacles. 20 25

In testimony whereof I affix my signature in presence of two witnesses.
